UNITED STATES PATENT OFFICE.

ROBERT G. MCAULEY, OF PITTSBURG, PENNSYLVANIA, ASSIGNOR TO THE MCAULEY AUTOMATIC TRAP COMPANY, OF PITTSBURG, PENNSYLVANIA, A CORPORATION OF PENNSYLVANIA.

CONTROLLING-VALVE FOR TRAPS.

SPECIFICATION forming part of Letters Patent No. 724,318, dated March 31, 1903.

Application filed October 13, 1902. Serial No. 127,152. (No model.)

To all whom it may concern:

Be it known that I, ROBERT G. MCAULEY, a citizen of the United States, residing at Pittsburg, in the county of Allegheny and State of Pennsylvania, have invented certain new and useful Improvements in Controlling-Valves for Traps, of which the following is a specification, reference being had therein to the accompanying drawings, forming part of this specification, in which—

Figure 1 is a vertical sectional view of a gravity-trap provided with my improved valve. Fig. 2 is a similar view showing the inner receptacle tilted, establishing communication with the piston of the outlet-valve. Figs. 3 and 4 are vertical sectional views of the valve on an enlarged scale, showing it in closed and open positions, respectively. Figs. 5 and 6 are horizontal sectional views indicated by the lines V V and VI VI of Fig. 4.

My invention refers to the class of traps for collecting and disposing of water of condensation or other liquid accumulation consisting of a vessel adapted to receive the liquid and to be automatically emptied by the operation of a gravity-actuated interior bucket adapted to open the valve mechanism, whereby the exhaust-port is opened and closed, so as to permit a constant fluid-pressure to discharge the contents of the trap.

The present invention relates more particularly to the valve controlling the flow of water from the vessel, the other portions of the construction conforming to the subject-matter of a similar invention for which Letters Patent were granted to me on January 7, 1902, No. 690,658.

Referring now to the drawings, 2 represents the main shell of the trap, to the top 3 of which or at any suitable location above the water-line is connected a pipe 4, communicating with any source of fluid-pressure, as a steam or gas conductor. Connected with the shell 2 also at any convenient location above the water-line is a water-supply or drain pipe 5, leading from any point in the line of pipe or vessel, by which pipe water of condensation is carried to the interior of the trap, and for the purpose of deflecting such water downwardly, so that it will not flow directly into

the bucket, I employ an arresting or deflecting shield 7, which shrouds the inner end of the opening, as shown.

Pivotaly mounted, as by a hinge-joint 8, upon the inner side of the case is a bucket 9, located about centrally of the interior, the opening at the top of which is preferably slanted downwardly toward one side, so that the water as it rises within the case around the exterior of the bucket will flow over such lower side, and so fill it. The bucket by reason of its buoyancy will float upon the water and be maintained in an erected position until so filled, when it will tip downwardly away from the hinge 8, as shown in Fig. 2, permitting the water to flow into it and to be exhausted from the case down to the level of such lower edge of the bucket. For the purpose of facilitating the tilting action a weight 10 of suitable size may be attached to the inner upper edge of the bucket in any convenient manner.

11 is an outlet-pipe extended down within the interior of the case and of the bucket to within a short distance of its bottom when raised, as in Fig. 1, and said outlet-pipe extends through the side of the case and communicates with the upper portion of a valve-chamber 12 above a vertically-moving valve located within the case and adapted when raised, as shown in Fig. 2, to establish communication from the interior of the bucket through pipe 11 and valve-case 12 and its outlet-opening 13, which may lead to any suitable point of discharge.

The shell 12 of the valve is preferably formed in one piece and is provided at its upper portion, somewhat below the level of the side connection for pipe 11, with a valve-seat 14, there being an annular space around said valve-seat for the purpose of receiving the upper supplemental pressure portion of the valve hereinafter described.

15 is a valve mounted on or formed integral with a stem 16, adapted to rest upon seat 14 and also close communication therethrough, and the valve is provided with an upper extended head 16' of considerable area, so that in the passage of the water through the pipe 11 it will be first delivered downwardly against

the top of said head 16 and will always exert a pressure thereon, tending to seat the valve. The annular space 17 around the valve enlargement is somewhat restricted, so that its 5 cross-area is less than the cross-area of the valve-opening leading to outlet 13, whereby the excess pressure from above will always act to seat the valve.

In the upper portion of the valve-case is a 10 cap 18, provided with a central cylindrical chamber 19, into which projects a plunger extension 20 of the valve-stem, through which is provided a reduced port 21. By this construction a water-cushion is maintained above 15 the plunger extension, serving to arrest a rapid upward travel of the valve and produce gradual movement by reason of the slow escape of the confined water through port 21. In the lower portion of the case below the 20 outlet-opening 13 is provided a piston-chamber 22, the lower portion of which is closed by a plug 23, having a central opening 24, with which connects a pipe 25, communicating, preferably, through an angle-valve with 25 port 26, leading to the interior of the case. The middle portion of plug 23 with opening 24 is extended upwardly within the interior of the piston-chamber, practically filling the space in the interior of the piston, and is 30 provided with lateral ports 27, below which water of condensation will collect and provide a water seal extending above the lower portion of the piston at all times, so as to act as a cushion through which the steam-pressure is exerted against its submerged periphery.

28 is the piston, provided with a series of annular recesses 29, adapted to be filled with water, so as to provide packing for the piston, 40 preferably having an upwardly-extending sleeve 30 and being connected to the piston-stem 16 in any suitable manner, as by screw-threads and nut 31.

A port 32 communicates with the interior 45 of the piston-chamber and with the outlet-opening, by which any accumulation of water or other counteracting pressure may be freely discharged.

33 is a drain-cock tapped into the side of 50 the valve-case immediately above the valve-seat for the purpose of drawing off water of condensation and preventing freezing.

The inner end of the port 26 terminates in a valve-seat 34, adapted to be closed by valve 55 35, which valve is formed or made on the inner end of a reciprocating stem 36, mounted in suitable bearings in the interior of the case. The valve-stem 36 is provided with adjustable abutments 37, between which a 60 bifurcated arm 38 is adapted to play and to move the valve-rod in or out by action against the abutments. This bifurcated arm is attached to and extends from the edge of the bucket 9, as shown, and in operation when the bucket is buoyantly held up 65 the valve will be maintained closed, relieving pressure from piston 28 by cutting off

the upper supply-pressure from above, keeping the outlet-valve 15 seated and allowing water of condensation to fill the interior 70 of the valve-case up to the level of port 27, thus submerging the lower end of the piston 28. When, however, water in the interior of the case has risen sufficiently high to overflow into the bucket and tip it by reason 75 of the specific gravity of the bucket itself and its counterweight, the tipping action of the bucket and the corresponding movement of the bifurcated arm 38 upon the valve 35 will open it and establish pressure to piston 28, 80 raising valve 15, whereupon the pressure within the case through pipe 4 will force the fluid contents of the bucket outwardly through pipe 11 until the water-level in the bucket is lowered down to the lower end of pipe 11, when 85 the bucket will rise upwardly, closing the valve and maintaining it so closed until the operation is again repeated.

The case 2 is provided at its lower point with a drain-cock 39, by which the case may 90 be emptied and accumulation of dust or other foreign material drained off. A feature of advantage in the construction is that all such accumulation of foreign material will settle to the bottom of the case, the clear water only 95 rising and flowing into the bucket, so that no foreign material will pass through the pipe 11 to the outlet-valve, whereby it is constantly maintained in a clear and operative condition. I also prefer to connect pipe 25 with plug 23 by 100 a coupling 40, having a reduced draining-port 41 by which water of condensation may escape.

The device may be used to drain any pipe or vessel where a pressure may be had, and 105 in its operation it is very efficient and reliable, obviating the objections of other kinds of traps for this purpose, and it will be found by those accustomed to this class of mechanism to give continued and satisfactory results.

The construction of the valve for controlling the escape of water from the interior is very simple, compact, and effective in operation, while the advantages of the extended 115 area of the valve insuring seating, the water-cushion in the upper end of the stem, the means for covering the lower end of the piston, together with the other features of the construction, contribute to the general efficiency and advantage of the invention.

The apparatus as a whole is very simple in construction, compact in size, symmetrical in form, and easy to build, while being reliable and efficient in continued operation and not 125 liable to get out of order.

While the construction of the valve, as well as the other portions of the invention, is well adapted to the objects in view, it will be readily understood that various changes and 130 modifications may be made in its construction or design by the skilled mechanic without departing from the invention as embodied in the following claims.

What I claim is—

1. A controlling device for traps consisting of a shell provided with a valve-seat, an inlet-opening above said seat, an outlet-opening below the same, a valve adapted to fit upon the seat provided with a supplemental peripheral pressure-surface, and a piston connected with the valve, with means for applying fluid-pressure thereto, substantially as set forth.
2. A controlling-valve provided with a hollow piston, a piston-chamber therefor, and a pressure-inlet conduit extending above the bottom of the chamber, substantially as set forth.
3. A controlling-valve provided with a piston, a chamber therefor, and a pressure-inlet conduit extending above the bottom of the chamber and provided with lateral ports, substantially as set forth.
4. A controlling-valve provided with a piston, a chamber therefor having a water-seal basin, and a pressure-inlet conduit terminating above the water-level thereof, substantially as set forth.
5. A controlling device comprising a case provided with a seat, an inlet-opening on one side of the seat, an outlet-opening on the other side thereof, a valve provided with a supplemental peripheral pressure-surface on the inlet side, and means for actuating the valve, substantially as set forth.
6. A controlling device comprising a case provided with a seat, an inlet-opening on one side of the seat, an outlet-opening on the other side thereof, a valve provided with a supplemental peripheral pressure-surface on the inlet side, and a piston secured to the stem of the valve, with means for applying pressure to the piston, substantially as set forth.
7. A controlling device comprising a case provided with a seat, an inlet-opening on one side of the seat, an outlet-opening on the other side thereof, a valve provided with a supplemental peripheral pressure-surface on the inlet side, and a hollow piston secured to the stem of the valve, with means for applying pressure to the interior of the piston, substantially as set forth.
8. A controlling device comprising a case provided with a seat, an inlet-opening on one side of the seat, an outlet-opening on the other side thereof, a valve provided with a supplemental pressure-surface on the inlet side, and an extended perforated plunger adapted to enter a corresponding recess in the case, with means for moving the valve, substantially as set forth.
9. A controlling device comprising a case provided with a seat, an inlet-opening on one side of the seat, an outlet-opening and an exhaust-passage on the other side thereof, a valve provided with a supplemental peripheral pressure-surface on the inlet side, an extended cushioning-plunger, a recess therefor, a piston-chamber, a communicating port between the piston-chamber and the exhaust-passage, a piston connected with the valve, and means for supplying pressure to the piston-chamber, substantially as set forth.
10. In combination with a trap provided with a pivotally-mounted vessel, an exhaust-pipe, and a pressure-valve actuated by movement of the vessel: a controlling-valve case communicating with the exhaust-pipe, a valve therein provided with a supplemental peripheral pressure-surface and a piston, a piston-chamber, and a connection between the piston-chamber and the pressure-valve, substantially as set forth.
11. In combination with a trap provided with a pivotally-mounted vessel, an exhaust-pipe, and a pressure-valve actuated by movement of the vessel: a controlling-valve case communicating with the exhaust-pipe, a valve therein provided with a supplemental peripheral pressure-surface and a piston, a piston-chamber, a water-seal cavity therein, and a connection between the piston-chamber and the pressure-valve, substantially as set forth.

In testimony whereof I affix my signature in presence of two witnesses.
